UNITED STATES PATENT OFFICE.

KARL RECKNAGEL, OF BOSTON, MASSACHUSETTS.

LIGHT-CONDUCTOR.

1,120,744.

Specification of Letters Patent.

Patented Dec. 15, 1914.

Application filed April 23, 1914. Serial No. 834,006.

To all whom it may concern:

Be it known that I, KARL RECKNAGEL, a citizen of the United States, and resident of Boston, county of Suffolk, State of Massachusetts, have invented an Improvement in Light-Conductors, of which the following description, in connection with the accompanying drawings, is a specification, like letters on the drawings representing like parts.

10 My present invention is an apparatus designed for receiving and conducting rays of light from outside a room or building to an inner portion thereof, together with provision for moving or adjusting the light conductor toward any desired point or object in the room.

My invention is particularly serviceable for use in photographic work for enabling light to be conducted from the exterior of 20 the building, as from a window, skylight, or other opening, directly on to an object or any part of the object, and furthermore, to secure the desired light and shade effects in a most direct and positive manner.

25 I have discovered that in using my improved light conductor, especially in photographic work, it is usually unnecessary to manipulate and adjust light curtains, light screens, shades, and the like, to secure proper 30 shadow and light effects, as the same can be obtained and in much more simple, easy and satisfactory manner by a simple adjustment of the light conductor. I may also desire to use a reflector outside the building to assist 35 in throwing the rays of light through the light conductor and can secure marked light and shade effects by adjusting the angle of this reflector as well as the adjustment of the position, length, and size of the light conductor itself.

40 I prefer to make the light conductor in the form of a telescoping funnel-shaped tube and to provide means to adjust the inner end thereof toward or away from the object 45 as may be desired. My light conductors may be made of paper, paper pulp, very light metal or the like, and may be adjustably supported in any suitable manner, as by ropes and pulleys, stands, or otherwise. I 50 may also make such conductors rectangular in cross section, or of other suitable shape for the particular work in hand, a rectangular conductor being preferable where a light conductor of such dimensions is de-

sired in certain classes of work, such as in 55 taking full length photographs. In either form, tubular, or rectangular, I prefer to provide a light obstructing flange around the open edge of the exterior of the tube, as I find that this construction produces the 60 best results.

Referring to the drawings, illustrating two forms of my invention, Figure 1 is a perspective view of a telescopic tubular light conductor positioned adjacent a window or 65 opening in the side of a room; Fig. 2 is a view, partly in cross section, of a rectangular conductor, also illustrating the position of a light reflector outside the conductor opening; and Fig. 3 is a view on a reduced 70 scale in cross section of the rectangular light conductor shown in Fig. 2.

The tubular light conductor illustrated in Fig. 1 comprises a plurality of telescoping sections 1, 2, 3, 4, 5, and 6, although a larger 75 or less number may be employed if desired. The conductor may be fitted in a window or attached to a swinging shutter 7 in the side wall 8 of a room. Preferably the outer portion 1 of the light conductor herein illustrated is provided with an edge flange 9 shown in dotted lines to cover up any light space in the opening in the swinging shutter 7 through which the portion 1 of the light conductor projects. An adjustable support 80 10 having a movable forked rest 11 held in any desired position as to height by a set screw 12 may also be provided to support the inner end of the tube. It will be readily appreciated that the telescoping members 85 90 may serve to shorten the light conductor and the stand 10 moved in desired supporting position to throw the light on the object, and obtain the desired light and shade effects.

In Fig. 2 I have illustrated a rectangular 95 form of light conductor 13, also attached to a swinging shutter 14 arranged on the side of a room, the conductor 13 being supported by ropes 15 and 16 extending over pulleys 17 and 18 respectively, and leading to any 100 desired point where it may be manipulated and secured to a cleat on the side of the wall (not shown) as will be readily understood. The conductor 13 is also provided with a peripheral flange 19 similar to the flange 9 on the tubular conductor illustrated in Fig. 1. The light reflector 20 pivotally hinged to the outside of the building and

held at a convenient angle by a cord 21 is shown, a similar reflector being used with the tubular conductor illustrated in Fig. 1, if desired. This reflector 20 is preferably of plain white material, as of cardboard or enameled metal surface, and may be angularly adjusted to give increased or decreased reflection of light through the conductor. The rectangular conductor 13 may also be 10 made of telescoping members if desired.

The two types of conductors herein shown are for illustrative purposes only, it being obvious to those skilled in the art that a suitable form, type or length of conductor 15 may be employed, and that it may be adjustably fitted in any manner desired, either to a window, to a special opening, or from a skylight or roof in the building. While this type of light conductor is of special 20 value in photographic work, it may also be utilized to transmit light to dark corners or remote portions of a room or building, thus enabling work in such room to be performed 25 by daylight much longer than would otherwise be possible, and thereby saving the expense of artificial illumination.

Having described my invention, what I

claim as new and desire to secure by Letters Patent is:

1. An apparatus of the kind described, comprising a light conducting member extending outside a room, and with its inner end movable to different positions to diffuse light within the room.

2. An apparatus of the kind described, comprising a light conducting member extending outside a room, having an opaque flanged portion around the outer opening, and with its inner end movable to different positions to diffuse light within the room.

3. An apparatus of the kind described, comprising a telescopic light conducting member extending outside a room, with its inner end movable to different positions to diffuse light within the room, and means to 45 maintain said conductor in angularly adjustable positions.

In testimony whereof, I have signed my name to this specification, in the presence of two subscribing witnesses.

KARL RECKNAGEL.
